MAGAZINE STAND OR SIMILAR ARTICLE

Jon W. Hauser, St. Charles, Ill., assignor to Hawley Products Company, St. Charles, Ill., a corporation of Delaware

Application March 7, 1955, Serial No. 34,877

Term of patent 14 years

(Cl. D33—2)

FIG. 1

FIG. 3

Fig. 1 is a front elevational view of a magazine stand or similar article, embodying my new design;

Fig. 2 is a side elevational view thereof; and

Fig. 3 is a top plan view thereof.

The dominant features of the design reside in the portions shown in full lines.

I claim:

The ornamental design for a magazine stand or similar article, as shown and described.
